US00D777911S

(12) **United States Design Patent** (10) Patent No.: **US D777,911 S**
(45) Date of Patent: ** Jan. 31, 2017

(54) **FEMININE PAD**(71) Applicant: **Kimberly-Clark Worldwide, Inc.**,
Neenah, WI (US)(72) Inventors: **Michael John Niemeyer**, Appleton, WI
(US); **Emily Nicole Schmitz**,
Hortonville, WI (US); **Susan Marie
Trefethren**, Appleton, WI (US); **Heidi
Bauerlein Hopkins**, Neenah, WI (US);
Mary Lou McDaniel, Appleton, WI
(US); **Katie Ann Boland**, Neenah, WI
(US); **Susan Mary Oates**, Appleton,
WI (US)(73) Assignee: **Kimberly-Clark Worldwide, Inc.**,
Neenah, WI (US)(**) Term: **14 Years**(21) Appl. No.: **29/465,622**(22) Filed: **Aug. 29, 2013****Related U.S. Application Data**

- (62) Division of application No. 29/381,682, filed on Dec.
22, 2010, now Pat. No. Des. 692,557.
(51) LOC (10) Cl. 24-04

EP 0 554 565 A1 8/1993

Primary Examiner — T. Chase Nelson*Assistant Examiner* — Michelle E. Wilson(74) Attorney, Agent, or Firm — Kimberly-Clarke
Worldwide, Inc.(57) **CLAIM**We claim the ornamental design for the feminine pad, as
shown and described.**DESCRIPTION**The sole FIGURE is a top plan view of the feminine pad of
the present invention, in which the claim is directed to only
the solid-line perimeter top edge.The broken lines shown are for the purpose of illustrating
environmental structure and form no part of the claimed
design.**1 Claim, 1 Drawing Sheet**(56)
